United States Patent Office.

ALFRED CROSSLEY, OF BROOKLYN, NEW YORK.

Letters Patent No. 72,458, dated December 24, 1867.

IMPROVEMENT IN STEAM-ENGINE GLOBE-VALVES.

The Schedule referred to in these Letters Patent and making part of the same.

TO ALL WHOM IT MAY CONCERN:

Be it known that I, ALFRED CROSSLEY, of Brooklyn, Kings county, New York, have invented a new and improved Valve; and I do hereby declare that the following is a full, clear, and exact description thereof, which will enable others skilled in the art to make and use the same, reference being had to the accompanying drawing, forming part of this specification.

The drawing represents a vertical sectional view of my invention.

This invention relates to a new valve for steam and water-pipes, and consists in such an arrangement of the parts, that the packing is below the screw-thread by which the stem is moved in the bonnet, so that the water will not come in contact with the screw-thread. The invention also consists in the arrangement of a recess or chamber, within the upper part of the bonnet, around the valve-stem; said recess being above the screw-thread.

The object of not carrying the screw-thread in the bonnet to the upper part of the bonnet, is to prevent the scraping of the upper smooth portion of the valve-stem.

As the valve-stem is, especially for water-works, generally protected by electro-plating, and, as the thin coat can be easily scratched off by the action of the female-screw thread in the bonnet, the screw-thread has been made so short that it will not come in contact with the smooth part of the valve-stem.

By arranging the packing below the screw-thread, water and steam are excluded from the screw-thread, and the latter will therefore not be ground off by impurities contained in the water or liquid. In water-works, the thread is generally quickly worn, as sand and other impurities enter between the windings of the thread and destroy the same.

A represents a steam or water-pipe, having an elbow, B, and a valve-seat, C, as usual. D is the valve-stem, having a screw-thread, *a*, formed around it at or near its middle. E is the bonnet, by which the upper end of the elbow is closed. The bonnet is perforated, to allow the passage of the valve-stem D.

A female-screw thread, *b*, is formed in the perforation of the bonnet, corresponding with the thread *a* on the stem D. The thread *b* does not extend to the upper end of the bonnet, but above it. The perforation of the bonnet is enlarged, forming a chamber, *c*, as shown. The smooth upper part of the stem cannot be scratched or injured by the screw-thread *b*, and its coat of electro-plating will remain intact. Below the screw-thread *b*, the perforation of the bonnet is enlarged to receive a nut, *d*, which presses a leather or India-rubber washer, F, against a shoulder in the bonnet, as shown. Water or steam is, by means of this packing F, excluded from the inner part of the bonnet, and consequently also from the screw-threads *a* and *b*, for purposes heretofore set forth. The lower end of the stem D is swivelled into a valve, G, and its upper end is provided with a suitable handle or hand-wheel, H.

Having thus described my invention, what I claim as new, and desire to secure by Letters Patent, is—

1. The chamber *c*, in the upper part of the bonnet E, above the screw-thread, by which the valve-stem is raised and lowered, so that the smooth upper part of the valve-stem will not come in contact with the screw-thread in the bonnet, substantially as herein described.

2. The arrangement of the packing F, bonnet E, and its recess *c*, whereby to exclude water or steam from the screw-thread in the interior of the bonnet, substantially as herein shown and described.

ALFRED CROSSLEY.
